UNITED STATES PATENT OFFICE.

HUBERT KRANTZ, OF NEW YORK, N. Y.

RECEPTACLE AND ATTACHMENT-PLUG.

SPECIFICATION forming part of Letters Patent No. 752,456, dated February 16, 1904.

Application filed October 24, 1903. Serial No. 178,411. (No model.)

To all whom it may concern:

Be it known that I, HUBERT KRANTZ, a citizen of the United States of America, residing in the borough of Brooklyn, city of New York, county of Queens, and State of New York, have invented an Improved Receptacle and Attachment-Plug, of which the following is a specification.

This invention has for its object to improve the construction of such receptacles as are used in electric wiring in conjunction with attachment-plugs, a further feature of my invention being the providing of said receptacle with a suitable inclosing box in which it may be protected from injury.

In the accompanying drawings, Figure 1 is a plan of my improved receptacle. Fig. 2 is a plan of the inclosing box with cover and receptacle removed. Fig. 3 is a view similar to Fig. 2, but with the receptacle in place. Fig. 4 is a section on line 4 4, Fig. 3. Fig. 5 is a section on line 5 5, Fig. 3. Fig. 6 is a transverse sectional view of an attachment-plug for use with this receptacle. Fig. 7 is a plan of said plug; and Fig. 8 is a plan, and Fig. 9 a side view, of the binding-post and contact-post to be used in the receptacle.

The receptacle R is formed of slate, fiber, porcelain, or other suitable insulating material. I have shown it formed of a cylindrical block. In this block are circular main recesses 2 and additional circular recesses 3, the additional recesses being formed in the block of greater depth than the main recesses. Each main recess is open to the adjacent additional recess. Two passages 14 are formed entirely through the block, each passage opening at its upper part into the adjacent recess 2 and in like manner to the recess 3, Fig. 5. Within each recess 2 is mounted a disk D, having a pair of semicircular clips C, which constitute a contact-post fitting into the additional recess 3. The disk D may be secured by screws 6, passing from the under side of the insulating-block, Fig. 5, and each disk has a binding-screw S, which serves to bind a conducting-wire w, entering through the passage 14.

The described receptacle is preferably in-

closed in a box B, which has an outwardly-turned flange f, provided with tapped holes t t and countersunk holes h h. At its lower end the box B has an inwardly-turned flange f', provided with tapped holes h' h'.

In placing the box in position in a building the electric wires are run through the open center at the bottom of the box, which is secured to the wall or floor by screws passing through the holes h h. The receptacle R is then placed in position with the conducting-wires passing through the passages 14, and fastening-screws s s are passed through openings in the block and screwed into the tapped holes h' h'. The wires w are then connected up and secured by the binding-screws S. A cover C, having two insulated bushings b b, is then fastened to the box by screws 10 10, which engage in the tapped holes t t in the flange f' of the box B, Fig. 10. These bushings and the holes which they protect are directly in line with the recesses 3, which contain the clips c.

An attachment-plug A, which I prefer to use in connection with this receptacle, is shown in Figs. 6 and 7. It comprises a block of insulation having a central opening 11 for the wires x, which branch out at opposite sides into the enlarged lower end 13 of openings 12, which have also enlarged upper ends 18. The contact-posts P are tapped at their upper ends 80 and are also provided with fixed collars 15 and washers 16. The wires x are connected up between the fixed collars and washers and securely held by the tightening of screws 17, bearing on shoulders in the enlarged upper 85 ends 18 of the openings 12.

I claim as my invention—

1. A receptacle for an attachment-plug, having a main recess and an additional recess, a contact-post and an attached disk, the disk being in the main recess, and the post in the additional recess, and a binding-screw carried by the disk, and a cover-plate provided with an opening in line with the additional recess, substantially as described.

2. A receptacle for an attachment-plug, having a main recess open at the top and an opening 14 through the receptacle from the bottom

to the side of said recess, with a disk in said recess, carrying a contact-post and a binding-screw, substantially as described.

3. A receptacle for an attachment-plug, having a circular main recess open at the top, a circular opening through the plug having one end opening to the main recess and a disk in said recess with a contact-post and binding-screw carried by said disk, substantially as described.

4. A receptacle for an attachment-plug, having a block with a circular main recess, a circular opening through the block for a wire, and a circular additional recess open at the top for a binding-post, both the circular opening and the additional recess, being opened into the circular side of the main recess, a disk and binding-screw within the main recess and a binding-post attached to the disk and within said additional recess, substantially as described.

5. An attachment-plug, having a main recess and an additional recess parallel thereto, a disk secured on the bottom of the main recess, and clips secured to said disk, but extending into said additional recess, substantially as described.

6. An attachment-receptacle, comprising an insulating-body part carrying the contacts, a metallic box therefor open at both ends, to which it is secured, said box adapted to be secured to the wall, a cover for the receptacle

adapted to be secured to the box, and insulated openings in the cover for the plug, substantially as described.

7. The combination of a circular box having an outwardly-turned flange at the top and an inwardly-turned flange at the bottom, and a circular receptacle secured therein, said receptacle having contact-posts at its upper part, a cover attached to the outturned flange of the box and having insulated openings in line with said contact-posts, substantially as described.

8. The combination of a circular open-end box having an outwardly-turned flange at the top and an inwardly-turned flange at the bottom, and a circular receptacle secured therein, said receptacle having contact-posts at its upper part, a cover with insulated openings attached to the outturned flange of the box in line with said contact-posts, and openings through the receptacle communicating between the open lower end of the box and the contact-posts at the upper part of the receptacle, substantially as described.

In testimony whereof I have signed my name to this specification in the presence of two subscribing witnesses.

H. KRANTZ.
